Organized Living freedomRail Shelf Locators, Date: prior to filing of application, 3 pages.

Primary Examiner — Mark A Goodwin

(74) Attorney, Agent, or Firm — Dinsmore & Shohl LLP

(57) **CLAIM**

The ornamental design for shelf locator, as shown and described.

DESCRIPTION

FIG. 1 is a front perspective view of a shelf locator showing our new design;

FIG. 2 is a front view of FIG. 1;

FIG. 3 is a rear view of FIG. 1;

FIG. 4 is a right view of FIG. 1;

FIG. 5 is a left view of FIG. 1;

FIG. 6 is a top view of FIG. 1; and,

FIG. 7 is a bottom view of FIG. 1.

The broken lines in the drawings are included for the purpose of illustrating environmental structure and forms no part of the claimed design.

1 Claim, 7 Drawing Sheets(56)
